US0D1091488S

(12) **United States Design Patent** (10) **Patent No.:** **US D1,091,488 S**
(45) **Date of Patent:** **** Sep. 2, 2025**

(54) **REMOTE CONTROL WIRELESS**

(71) Applicant: **AUMA Riester GmbH & Co. KG**,
Müllheim (DE)

(72) Inventor: **Lars Meohofer**, Buggingen (DE)

(**) Term: **15 Years**

(21) Appl. No.: **35/521,779**

(22) Filed: **Jul. 5, 2024**

(80) **Hague Agreement Data**

Int. Filing Date: **Jul. 5, 2024**

Int. Reg. No.: **DM/238496**

Int. Reg. Date: **Jul. 5, 2024**

Int. Reg. Pub. Date: **Jul. 26, 2024**

Primary Examiner — Selina Sikder

(57) **CLAIM**

The ornamental design for a remote control wireless as
shown and described.

DESCRIPTION

1. Remote control wireless
2. Remote control wireless
- 1.1 : Perspective
- 1.2 : Perspective
- 1.3 : Front
- 1.4 : Back
- 1.5 : Left
- 1.6 : Right
- 1.7 : Top
- 1.8 : Bottom
- 2.1 : Perspective
- 2.2 : Perspective
- 2.3 : Front
- 2.4 : Back
- 2.5 : Left
- 2.6 : Right
- 2.7 : Top
- 2.8 : Bottom

Intended use of the product: Remotely controlling the status
of a valve actuator.

1 Claim, 16 Drawing Sheets
